Harold G. Fitz Gerald,
By Alfred H. Daehler
HIS ATTORNEY

UNITED STATES PATENT OFFICE.

HAROLD G. FITZ GERALD, OF LOS ANGELES, CALIFORNIA.

LAMP.

Application filed January 26, 1920. Serial No. 354,184.

To all whom it may concern:

Be it known that I, HAROLD G. FITZ GERALD, a citizen of the United States, residing at Los Angeles, in the county of Los Angeles and State of California, have invented new and useful Improvements in Lamps, of which the following is a specification.

This invention relates to lamps, and more particularly to lamps comprising a reflector or other casing, a glass through which the rays from a source of illumination are projected, and means for securing the glass in position in connection with the reflector or other casing; in the manufacture of lamps for motor vehicles and the like, many forms of devices for so uniting the glass and body portions are employed, and as quick detachability of the glass from the other lamp portions is desirable, in order to replace the glass when broken or the electric light globe, in case of an electrical source of illumination, or for other reasons, it is the object of this invention to provide a lamp embodying improvements of the above general nature; furthermore, it is highly desirable that a dust and moisture proof joint be made at the junction of glass and other lamp portions, as well as having a snug fit between all such portions to prevent rattling and other apparent disadvantages.

In accordance with the invention, the reflector or casing of the lamp body in the preferred form thereof, is provided with a flared edge or peripheral portion, against which the glass at or near its periphery may be seated, or in which the glass may be received, and an annulus of U-cross-section is applied over the glass and the reflector or casing portion; such annulus comprises a preferably metallic band or strap adapted to have its ends united after positioning over the glass and flared portion of the reflector or casing; at one end the strap is provided with a hook, and at its other end such strap has a longitudinally ranging series of perforations into one of which the hook is pressed. The strap being of channel or U-section, as hereinbefore stated, and with the channel at the inner face thereof, the channel may be lined with a sealing strip or element

of felt or other suitable packing material which preferably has sufficient inherent resiliency to yieldingly oppose application of the strap to the portions above mentioned, to the end that after the strap is tightened and the catch or hook at one of its ends is sprung into a notch in the other end of the strap the outward pressure of the packing strip will prevent accidental displacement of the annulus comprising the strap with its suitably formed ends. However, the parts may be readily separated by pulling outwardly on the hooked end of the annulus.

With the above and other objects in view, the invention consists in the novel and useful provision, formation, combination and interrelation of parts, members and features, all as hereinafter described, shown in the drawing and finally pointed out in claims.

In the drawing:

Figure 1 is a side elevation of a lamp body embodying the invention;

Figure 2 is a front elevation of the showing in Figure 1;

Figure 3 is an enlarged fragmentary sectional view taken on the line x^3-x^3 , Figure 1, and looking in the direction of the appended arrows; and

Figure 4 is a sectional view taken on the line x^4-x^4 , Figure 3, and looking in the direction of the appended arrows.

Corresponding parts in all the figures are designated by the same reference characters.

Referring with particularity to the drawing, in the embodiment of the invention therein shown, 5 designates a casing or reflector having a support 6, 7 designates a glass through which the rays of the lamp are projected, 8 designate means for securing the casing 5 and glass 7 in assembled position, 9 designates sealing means adapted to yield under compression by the securing means 8, and 10 designates a source of illumination disposed in the casing 5.

The casing 5 is preferably formed of suitable metal, and in the form of the invention shown has an inner parabolic reflecting surface 11; the support 6 is shown as joined to the casing 5 at the rearward end thereof and as comprising a swivel member adapted to be pivotally secured to suitable supporting

means, not shown, so adapting the lamp for use as a spotlight for use in connection with motor vehicles and the like; the source of illumination 10 preferably comprises an electric lamp or globe having a base 12 fitted into a lamp socket or tube 13 which passes through a suitable longitudinal bore at 14 in the support 6, the reflector or casing per se, being, of course, correspondingly apertured; 10 the globe and a portion of its supporting socket are shown in dotted lines in Figure 1. An adjusting screw 15 may be threaded into a suitable aperture in the wall of the support 6 and tightened against the lamp socket to hold the lamp in its properly focused position. At its forward edge the reflector or casing 5 has an outwardly and forwardly flaring peripheral seat 16 in which the peripheral or edge portion of the glass 7 is received or against which such peripheral portion of the glass may be seated. This will be readily understood by reference to Figure 3 of the drawing.

20 The glass 7 is shown as a circular pane of convex form with its edge portion received or seated in the seat 16 as just described, the convex side of the glass projecting forwardly.

25 The securing means 8 comprises an annulus 17 preferably formed of a strap of metal the ends of which are adapted to be joined when the annulus is applied over the glass and casing; the strap is formed to produce an inwardly directed channel 18 and 30 is preferably U-shaped in cross-section, and in the form shown in the drawing, the front face 19 is slightly wider than the other face 20; at one of its ends 21 the strap carries an inwardly directed hook or tooth 22 and at 35 its other end 23 the strap has a series of tooth-receiving notches or slots 24; the series of slots 24 ranges lengthwise of the strap and the distance between adjacent slots preferably is slight so that the annulus may be 40 properly adjusted when placed over the glass and reflector or casing. The tooth 22 engages one of the slots 24 and bears against one of the bars 25 resulting from the slotted formation in the strap end 23. It is plainly 45 apparent that this not only forms a rigid means for holding the parts together, but also brings about a very simple and neat appearing device. In the preferred form of the invention the hook or tooth 22 is formed 50 on one end of a clip 26 of U-section.

55 The clip 26 is preferably applied to the strap end 21 by inserting an inwardly directed prong 27 into and through a slot 28 in the clip-carrying end of the strap forming the major portion of the annulus and bending the same to form a hook as shown in Figure 4, after which these parts may be united as by soldering as at 29; however, the prong 27 and slot 28 may be omitted and the 60 clip united directly with the other annulus 35

portion as by soldering, welding or the like, or the toothed end of the strap may be formed in any other suitable manner without departing from the invention.

65 The yielding or compressible sealing means 9 may comprise a strip of felt, adhesive tape, or other suitable material; adhesive tape applied to the marginal portion of the glass 7 and the flared peripheral portion of the reflector, after the glass has been seated therein or thereagainst, the channelled annulus being applied over such tape, has proven in practice to be a good material for use as a combined packing and annulus holding element. 70

75 In the use of the invention, the glass and reflector may be assembled and the yielding packing element either applied, over the marginal portions of the same, or positioned in the channel of the annulus, according to the material used and the preference of the user of the invention. The annulus with its ends separated is applied to the reflector casing and glass. The tooth or catch 22 may then be pressed into the proper notch 24 and catch against the corresponding bar 25; the series of closely grouped bars 25 provides for the presentation of a bar 25 to the tooth or catch 22 at just the right point to provide for the desired degree of annulus 80 constriction against the other parts to properly hold the same in assemblage without rattling, accidental displacement of parts, or other disadvantages; the compressible or yielding packing or sealing element 85 9 acting outwardly against the annulus causes the hook or catch 22 to tightly engage the caught bar 25 so preventing accidental opening or dislodgement of the annulus. 90

95 To remove the glass 8, to substitute a new glass for a broken one, or for the purpose of substituting a new lamp globe 10 for a burned out one, or for other purposes of lamp repair or adjustment and the like, it is only necessary, in order to remove the annulus, to grasp the clip 26 between the fingers and pull outwardly thereon, or otherwise lift or pry the toothed end of the annulus out of engagement with the engaged bar 25. The packing element preferably holds the 100 annulus out of direct engagement with the glass and casing as shown in Figure 3. 105

110 Having thus disclosed my invention, I claim and desire to secure by Letters Patent:

1. In a device of the character described, 115 a, casing, a glass applied to said casing, a packing element applied to said casing and glass, a U-shaped band to hold said casing and glass rigidly in position when affixed thereto, slots formed in said band adjacent one end, an inwardly extending lug formed integral with the other end which fits any one of said slots. 120

125 2. A spot light comprising a casing, a lens, a lens securing device comprising an annular 130

member which is U-shaped in cross-section, there being a plurality of slots formed in the arc of the U adjacent one end of said band, an inwardly extending lug integral with said band and an elastic packing intermediate the band and the lens.

In testimony whereof, I have signed my

name to this specification in the presence of two subscribing witnesses.

HAROLD G. FITZ GERALD.
